UNITED STATES PATENT OFFICE.

GEORGE C. LANDIS, OF CONNELLSVILLE, PENNSYLVANIA.

COKE-DRAWER

No. 861,292

Specification of Letters Patent.

Patented July 30, 1907.

Application filed January 29, 1907. Serial No. 354,775.

To all whom it may concern:

Be it known that I, GEORGE C. LANDIS, a citizen of the United States, residing at Connellsville, in the county of Fayette and State of Pennsylvania, have invented or discovered new and useful Improvements in Coke-Drawers, of which the following is a specification.

My invention relates to coke drawers and its object is to provide a machine which may withdraw the entire charge of a coke oven at a single operation. Preferably, 10 the machine will draw the coke out upon a platform forming a part of the machine. I prefer to mount the machine upon a track extending along a row of ovens, so that the charge from any oven may be accessible to the same.

15 Referring to the drawings accompanying this specification, Figure 1 is a longitudinal section of a coke oven with my machine in side elevation, the drawing device being shown ready to withdraw a charge of coke; Fig. 2, a horizontal section of the coke oven and a plan of my 20 machine in the relative position shown on Fig. 1; Fig. 3, an elevation of Fig. 1 looking to the right; Fig. 4, a section on the line 4—4 of Fig. 2; Fig. 5, a detail showing the method of raising and lowering the drawing device; and Fig. 6, a section on the line 5—5 of Fig. 4.

25 On the drawings, 1 designates a coke oven having the base 2, the roof 3, the parallel sides 4, and the end openings 5, the latter being shown with the doors or filling removed.

7 is the usual trunnel hole.
30 8 represents a track extending along the end of a row of coke ovens.

My coke drawing machine is made in the form of a truck or carriage supported on the wheels 9, which run on the track 8 so that the truck may be placed 35 opposite any oven in the row.

10 is the platform or bed of the carriage, its upper surface being at the level of the floor 11 of the oven. The carriage supports the electric or other motor 12, which through the gearing 13 drives the pinions 14, 40 one at each side of the platform supported in short shafts 15 above the level of the platform but not extending across the same. The shafts 15, 15 are provided with the gears 16 meshing with the pinions 17 on the shaft 18 extending from one side of the carriage to the other beneath the platform. None of the shafts for 45 the gearing runs above the platform, as the space above the same must for the height of the coke be kept entirely clear to enable the coke to pass over the platform without obstruction. The pinions 14 mesh with the racks 19 on the lower edges of the parallel sides 20 of the coke drawing tool, the forward ends of the said sides being joined together by the cross piece or bar 21. The sides 20 are spaced so as to substantially reach from one wall 4 to the other, but the spacing may be varied. 55 Preferably the pinions 14 have their peripheries grooved to receive and guide the sides 20. The

sides 20 will be long enough to permit the bar 21 to reach to the most distant part of the coke in the oven without causing the racks 19 to be out of mesh with the pinions 14. The upper edges of the sides 20 are guided by the grooved rollers 22 having a yielding motion up and down the standards 23, which support these rollers as well as the pinions 14. The tops of these standards are tied together by the bar 24. The front end of the carriage supports the two standards 25 tied together by the bar 26. Each standard 25 contains and guides a vertically movable rack-bar 27, actuated by the pinions 28 on the shaft 29 beneath the platform. The shaft 29 may be rotated by the handle 30 and prevented from turning backward by the pawl 31. The rack bars each 70 carry two grooved wheels 32 in which the opposite edges of the sides 20 are guided and held in place.

The operation is as follows: The end of the oven 1 nearest the carriage being opened, the latter is brought opposite the same with the drawing tool retracted to 75 the left. The handle 30 is rotated to elevate the tool so that the bar 21 may enter the oven above the coke shown by the dotted line 33. The motor 12 is started in a direction to push the tool into the oven and during this movement of the tool, the handle 30 will be turned 80 so as to direct the bar 21 up over the coke as shown in dotted lines in Fig. 1 and down at the rear thereof, as shown in full line in the same figure. The motor is now reversed, the bar 21 pulling the coke out upon the platform. As the carriage is not so wide as the charge of 85 coke is long, a portion of the charge will be pushed beyond or off the carriage. A car may be placed so as to receive the projecting portion as it falls or breaks off. It is not necessary to clear the coke from the platform after each drawing operation, as the next charge drawn 90 will engage it and force it off therefrom, as will be readily understood.

I do not desire to be restricted to the precise construction shown as the same may be varied greatly 95 within the limits of my broadest claims.

I claim—

1. In a coke drawer, a coke drawing tool comprising a pair of side bars, and a cross bar joining their outer ends in combination with means in engagement with their inner ends for withdrawing from a coke oven a charge of coke 100 between said side bars and in front of the cross bar.

2. In a coke drawer, a pair of side bars provided with rack teeth, a cross bar joining their outer ends, pinions meshing with said rack teeth, and means for rotating said pinions, the space between the side-bars being left open so that the said cross-bar may withdraw the coke from the oven when the side-bars are actuated by said pinions so as to withdraw them from the oven.

3. In a coke drawer, a pair of side bars provided with rack teeth, a cross bar joining their outer ends, pinions 110 meshing with said rack teeth, means for rotating said pinions, and means for oscillating the tool on said pinions as a center.

4. In a coke drawer, a pair of side bars provided with rack teeth, a cross bar joining their outer ends, pinions 115

meshing with said rack teeth, means for rotating said pinions, means for oscillating the tool on said pinions as a center, and yielding means for holding the rack teeth in engagement with the pinions.

5. In a coke drawer, a pair of side-bars provided with rack teeth, a cross bar joining their outer ends, pinions meshing with said rack teeth, means for rotating said pinions, means for oscillating the tool on said pinions as a center, a pair of vertically slidable bars, means on said

10 slidable bars for guiding and supporting said tool, and means for raising and lowering said slidable bars.

6. The combination of a carriage mounted to travel in front of a row of coke ovens, a platform on said carriage substantially at the level of the oven floors, and a pair of

side-bars on the carriage spaced apart substantially the 15 width of the oven chamber, means carried by the forward ends of the side-bars for engagement with the rear side of the charge of coke in the oven, and means on the carriage for withdrawing the side bars with the charge of coke from the oven, said last named means being arranged to 20 leave the space opposite the front of the oven open for the passage of the entire charge of coke over the said platform.

Signed at Pittsburgh, Pa. this 28th day of January 1907,
GEORGE C. LANDIS.
